Term of patent 14 years

(Cl. D80—9)

Fig. 1

FIGURE 1 is a perspective view of a rack for displaying books, cameras and the like, showing my new design; FIGURE 2 is a top plan view thereof; and

The broken line representations of books and cameras in FIGURES 1 and 2 are for purposes of illustration only.

This is a continuation-in-part of design application Serial No. D.85,790, filed June 17, 1965, now abandoned.

I claim:

The ornamental design for a rack for displaying books, cameras and the like, as shown and described.
